I. DROLSHAMMER

RAILWAY BRAKE

Filed May 26, 1923

Fig. 2.

Fig. 1.

UNITED STATES PATENT OFFICE.

IVAR DROLSHAMMER, OF DRAMMEN, NORWAY.

RAILWAY BRAKE.

Application filed May 26, 1923. Serial No. 641,663.

To all whom it may concern:

Be it known that I, IVAR DROLSHAMMER, a subject of the King of Norway, residing at Drammen, Norway, have invented certain new and useful Improvements in Railway Brakes, of which the following is a specification.

My invention relates to railway brakes and more especially to automatic compressed-air brakes for railway trains and the like, and the object of my invention is to render it possible to supply the compressed air at first rapidly in order to apply the brake shoes to the wheels, but slower after a certain brake pressure has been reached, this slower supply being maintained until the final pressure required or desired in the individual case has been attained.

With long trains, especially goods trains, it is desirable to make the brake pressure, when starting braking, rise at first rapidly to a predetermined limit, say 0.6 atm., in order to brake all the cars as quickly as possible, but with comparatively little power, whereby the buffers of the consecutive cars are made to touch each other and the train receives a certain stiffness. If then more compressed air is supplied in order to brake more powerfully, this shall take place far more slowly than in the range from 0 to 0.6 atm., the intention being to diminish the difference between the retarding forces acting at the head and the tail of the train, whereby the cause for the crowding or closing up of the cars, as well as for their mutual tugging is obviated.

With passenger trains and express trains which are not by far as long as goods trains, and the draw gears and buffer gears of which are as a rule of considerably better design than in goods trains, it may be desirable to make the brake pressure rise rapidly to its maximum in the case of quick braking. The present railway regulations demand that any railway car can be put in any train which is possible only, if the shape of the ascending portion of the brake-pressure curve and the highest brake power limit required at the time being can be changed by means of a change-over device according to the kind of train and the load of the cars.

In order to attain such regulation with regard to the brake pressure curve, there have hitherto been used so-called minimum pressure valves which involve, however, the

drawback of being very complicated and, therefore, causing disturbances of the service. The fundamental disadvantage of these valves resides in the feature that the time of braking and the time of releasing the brakes depend mutually on one another. Now, the braking time of a car running in a passenger train should amount to about 6 seconds, whereas if the same car is running in a goods train the braking time shall amount to about 45 seconds, as is the case, for instance, with the well known Kunze-Knorr brake. Thereby the releasing time of the brake is however extended from about 10 seconds to from 45 to 70 seconds, according to the length of stroke of the brake piston. This releasing time remains, anyhow, always the same, irrespective of whether the train consists of but one or a hundred cars. The manœuvring capacity of the brake is thereby greatly impaired which is very disadvantageous especially on mountain lines with various rises and many curves. Besides, the buying and maintenance costs of these valves are considerable and represent a great financial burden for the railway companies.

My invention fundamentally solves the problem of obtaining with certainty such a brake pressure curve with rapid rise to a certain low pressure and a slower increase from this pressure to the final pressure, without, however, affecting the releasing time of the brake. At the same time both the fundamental and the constructive deficiencies of the old minimum pressure valves shall be obviated. This is attained, first of all, by starting from a fundamental form of a compressed-air brake in which a control piston or the like is used (as shown, for instance, in German Patent 373,774) which is moved, in consequence of the changes of pressure caused in the main air supply pipe, into positions corresponding or proportional to these changes of pressure. This control piston and the appertaining control slide-valve proper, or the corresponding member of the brake control valve, jointly control the flow of the compressed air from the auxiliary air reservoir (and the main supply pipe) into the brake cylinder in such a manner that, on braking being started, air from the auxiliary reservoir (and the pipe) flows into the brake cylinder until the minimum pressure desired is attained. This pressure having

been attained, the strong flow of air from the auxiliary reservoir is automatically completely interrupted, as is also (or nearly so) the flow of air from the main supply pipe, so that from now on the braking air further required passes from the auxiliary reservoir into the brake cylinder either wholly or at least for its greatest part through a narrow throttling aperture and through the brake control valve, in consequence whereof the further rise of the brake pressure can take place but slowly.

The rapid admission of air to the brake cylinder through the brake control valve, as desired for the beginning is rendered possible by apertures which the control piston holds open until the desired brake pressure has been reached, said apertures forming, besides the possibility of the compressed air passing over directly, a secondary passage or a by-path which is shut off as soon as the pressure in question is surpassed, whereafter there remains only the direct way. As the braking air may be conducted in this manner to the brake cylinder over the auxiliary air reservoir, thus also the air present in front of the control piston may be conducted in the main pipe through the brake control valve to the brake cylinder, in which case the control piston shuts off again wholly or partly the by-pass aperture as soon as the predetermined definite pressure is reached. The change of form of the ascending branch of the brake pressure curve from the goods-train adjustment to the passenger train adjustment may be effected simply by altering the position of the shut-off cock of the brake cylinder valve, there being, for the rest, the possibility either to keep up the regularity, although in other dimensions, or to change the regularity as such.

In the drawings affixed to this specification and forming part thereof, a device embodying my invention is illustrated by way of example. In the drawings—

Figure 1 is a longitudinal section of the brake, and

Figure 2 is a longitudinal section of its shut-off cock.

Figure 3 is a cross-section of the middle part of Figure 1 in the axis of the cock.

Figure 4 shows in longitudinal section and

Figure 5 in cross section some details of the cylinder of the control piston.

Figures 6, 7 and 8 are cross sections through the shut-off cock showing it in three different positions.

Referring to the drawings, the control piston K which slides into a sleeve L in a valve casing D has a recess 4 and its rod d is provided at its free end with a bushing T¹ supporting one end of the coil spring F¹, the other end of which is located in a tubu-

lar cavity of the control slide valve s which forms a broad circumferential groove a between its flanged end and a broad circumferential rib provided with channels z and is loosely shiftable on the piston rod d.

This latter bears with its free end on a piston-like spring plate T² resting on a double spring F² which balances the pressure which the compressed air in the train pipe exerts on the control piston K. The spring F² is compressed when the brake is released, and means are provided for relieving the spring F² when the air pressure on the piston K exceeds a certain limit. The train pipe (not shown) is connected to a pipe e of the valve casing D, Fig. 3. A double non-return valve V¹, V² is inserted between the inner end of the pipe e and a passage E¹ connected with the auxiliary reservoir B which is shown broken off in Fig. 1. A passage E connects the reservoir B with the sleeve of a cock H in the valve casing D. The cock H is operated by a handle H¹. The passage E extends beyond the cock H and is connected with a chamber k³ which partly surrounds the sleeve L at the level of ports h in this sleeve (Fig. 3). Chamber k³ is connected with a longitudinal passage 6 extending along the outside of sleeve L to the level of ports 3 and 5 in this sleeve, as will best be seen in Fig. 5. An inclined passage l extends upward from the sleeve L at the level of port 3. Ports x¹, x² and x³ in sleeve L are connected by a longitudinal passage o¹. Another longitudinal passage o, o² connects the space above the sleeve L with a port w⁵ in the sleeve of the cock H (Figs. 3 and 4). Passages y connect a passage g which extends between the brake cylinder C and a port g¹ in the sleeve L with atmosphere unless blocked by the cock H.

The air from the inside of the sleeve L escapes through ports h in the sleeve L, if such ports are laid open by the flange of the slide valves s, holes i in the bottom plate i¹ of the casing, ports i² and i³ in the spring plate T² and a passage i⁴ at the end of the casing in which the spring F² is housed.

The device is here shown as adapted to a brake of the one-chamber type. The auxiliary reservoir B is charged with compressed air from the train pipe at the usual pressure, say 5 atm., through the pipe e. Charging of the reservoir is effected by means of the driver's valve, which is so adjusted as to supply to the auxiliary reservoir B air from the main reservoir of the locomotive in which air is stored under pressure, of, say, 8 atm. The pressure of the air is reduced to 5 atm. in the driver's valve and at this reduced pressure it is admitted to the auxiliary reservoir B from the train pipe and the pipe e through check valves V¹ and V² and passage E¹.

The cock H is provided with two ports w¹ and w² which are connected with the

and w^2 in the plane of the passage E and with two more ports w^3 and w^4 above the passage E¹. Port w^3 appears in Fig. 3. Port w^4 is in the same plane as the port w^3 , both ports being at an angle as shown in Fig. 4. The ports w^3 , w^4 are adapted to register with a port w^5 in the sleeve of the cock which port is connected with the passage o , o^2 .

10 In the position of the cock H shown in Figs. 1 and 6, which corresponds to the position II of its handle H¹ shown in dot and dash lines in Fig. 1, the apparatus is adjusted for the operation of goods trains. In this 15 position, the port w^4 of the cock registers with the port w^5 of the cock sleeve, connecting the pipe e with the passage o , o^2 .

In the case of a passenger or express train the cock H is turned clockwise into the position shown in Fig. 7 in which its handle H¹ is at I in Fig. 1 and the port w^3 registers with the port w^5 . When the pressure in the train pipe attains a certain limit, for instance, 3.5 atmospheres, the piston K begins 25 to move in a downward direction and compresses the spring F². The degree of compression of the spring is in proportion to the increase of pressure in the train pipe. In order to prevent overloading of the spring 30 F² in case of excessive pressure in the train pipe, a shoulder is provided in the casing of the spring F² on which abuts the spring plate T² when the pressure in the train pipe exceeds a certain limit. In the position of 35 parts shown in Fig. 1, the spring plate T² abuts on the said shoulder and the piston K is at the lower end of its stroke.

If the pressure in the train pipe (service braking) is reduced slowly, first the return 40 flow of the air from the auxiliary reservoir B into the pipe e is prevented by the closure of the non-return valves V¹ and V². The control piston K and with it the piston rod d with the spring plate T¹ are shifted a little 45 upwards until the air pressure on the piston K at the time being is equal to the tension of the spring F² at the respective time, whereby the control piston is caused to assume positions which are determined by and 50 are proportional to the pressure existing in the train pipe at the respective time. When shifting the control piston K, the control slide valve s is taken along with it by reason of the small tension of the spring F¹ then 55 arising and being corresponding to the friction of the balanced control slide valve whereby the discharge channels h for the air flowing over from the brake cylinder C are closed, whereas the admission channel k to the brake cylinder is opened (braking position). The compressed air can now, therefore, flow rapidly from the auxiliary air reservoir B into the brake cylinder C through the channel E, the large aperture 60 w^1 of the shut-off cock, the channels 1, 2, and

3, the recess 4 of the control piston K, the channels 5 and 6, the recess k¹, the channel 4, the recess a of the control slide valve s, and the aperture g¹ of the stationary guide sleeve L, and at the same time the compressed air flows into the space between the control slide valve s and the control piston K through the apertures z of this slide valve. This way of braking air is that which has above been termed "secondary passage" or "by-way" and has relatively large sectional areas for the passage of the air. Compressed air is, at the same time, flowing slowly to the passage k³ in the casing D through a narrow passage w² in the cock H 70 which is connected with the wide passage w¹. In the goods train position of the cock H shown in Fig. 1, the passage w² admits air to the port k³ as described. This air flows into the brake cylinder through the channels k, the recess a of the control slide valve s, the apertures g¹, and the branch g. This way, which is termed the "direct way," has thus smaller free sectional areas through 75 which the air is to pass.

Simultaneously therewith the control slide valve has opened the port x¹ of the sleeve L which is in equal height with the channels k, in consequence of which the amount of air pressed back into the pipe e by the control piston K whilst moving upwards (or, may be, a larger amount of air) is allowed to flow into the brake cylinder through the port x², the channel o¹, the port x¹, the recess a, the aperture g¹, and the branch g, whereby is attained that the drop of pressure propagates very rapidly and uniformly throughout the entire length of the train pipe along the train. The brakes of the rear cars of the train are, therefore, actuated just as quickly and uniformly as the brakes of the cars at the head of the train.

If the driver does not further reduce the pressure in the train pipe, the control piston K stops at once in the position determined by the reduction of the pressure, whereas compressed air can flow from the auxiliary air reservoir and the main admission pipe only until the axial back pressure on the control slide valves of the air filling the brake cylinder is equal to the compression of the spring F¹ as produced by the displacement of said slide valve. This valve is thus now shifted back into a position in which it again 110 shuts off the channels k and x¹. At another gradual reduction of the pressure the same procedure takes place, the brake pressure 115 being thereby increased.

If, in correspondence with a definite fall 120 of pressure in the train pipe, a brake pressure of, for instance 0.6 atmosphere is attained in the cylinder C, the control piston K has covered a definite path in upward direction. All conditions are now so chosen 125

that the control piston K shuts off the flow of the compressed air from the auxiliary air reservoir B over the brake control valve into the brake cylinder C through the large apertures w^1 , 1, 2, 3, 5 and 6, in that it closes the apertures 3 and 5, whereby the secondary passage or the by-path for the compressed air is shut off. Simultaneously with the further increase of the brake pressure by the engine driver reducing the pressure in the train pipe, the compressed air from the auxiliary air reservoir B¹ can get to the brake cylinder only on the direct way, that is to say through the narrow throttling aperture w^2 of the cock H. The brake pressure rises from this time only slowly, corresponding to the size of the throttling aperture w^2 so that the braking time may be determined to about 40 seconds.

In order to prevent the compressed air which flows over from the train pipe into the brake cylinder through the aperture x^3 , the channel o^1 and the aperture x^1 from being a hindrance to the slow rise of the brake pressure, the control piston K closes the apertures 3 and 5 and the aperture x^3 at the same time whereby also the strong flow of air from the train pipe ceases as soon as a brake pressure of, for instance, 0.6 atmosphere has been reached. If the state of the service should make it desirable to have quite a small quantity of compressed air flow over from the train pipe into the brake cylinder after the brake pressure of, for instance, 0.6 atmosphere has been reached, the guide sleeve L may be provided with a narrow passage aperture (not shown) which the control piston shuts off only in its highest position.

In order to accommodate the automatic flowing over of the air from the train pipe particularly well to the conditions of the service, the sleeve L is provided, besides the aperture x^1 , with a larger aperture x^2 which is uncovered by the control slide s when the driver reduces quickly the pressure in the train pipe. The compressed air can then flow from the main admission valve into the brake cylinder C through the two apertures x^1 and x^2 , that is to say still quicker than above described. Simultaneously with the gradual pressing back of the control slide valve s under the counter-pressure arising in the chamber a^3 , first the aperture x^2 is closed so that only the aperture x^1 remains at disposal.

If the shut-off cock H is turned over from the position shown in Figures 1 and 6 which is the goods-train position to the position illustrated in Figure 7 which is the passenger-train position, compressed air flows always rapidly, in unthrottled state, from the auxiliary air cylinder B into the brake cylinder C through the large aperture w^1 of the shut-off cock H, the recess k^3 , the ad-

mission aperture k , the recess a of the control slide valve s, the apertures g^1 and the branch g , the flow of the air continuing until the normal brake pressure has been reached, the braking time being diminished from 40 seconds, as above assumed, to for instance 6 seconds without affecting the normal releasing time and the regulating at liberty of the brake pressure. The shut-off cock may, however, be so devised that also for the passenger-train adjustment per se the same regularity as with the goods-train adjustment may be kept up; that is to say, the narrow direct way and the larger secondary way over the aperture controlled by the control piston k, only the proportions as regards the dimensions being different.

If the shut-off cock H is turned into the shutting position shown in Figure 8, the auxiliary air reservoir B is completely closed whereby the compressed air is therein retained. If the brake was, however, applied, the compressed air flows now from the brake cylinder C into the open air through the discharge channel y and the large aperture w^1 of the shut-off channel y .

In order to render possible varying the strength of the braking power in correspondence with the load of the car or cars at the time being, the brake control valve is provided with a special top as illustrated in Figure 1, but as this top does not form part of the subject-matter of this application, I abstain from entering into details as to its construction and manner of operation. Mention may be made, however, of the modification that the throttling apertures need not be arranged in the cock plug, but may be provided in the cock casing.

I claim:—

1. A compressed-air railway brake of the type in which on initiating the braking the brake pressure rises at first rapidly up to a predetermined low limit, whereas the further rise proceeds but slowly, characterized thereby that the control piston which is moved into positions corresponding to the air pressure existing in the train pipe and being determined by the adjustment of the driver's brake valve controls, together with the control slide valve proper of the brake control valve, the flowing over of the compressed air into the brake cylinder in such a manner that on initiating the braking, the air can flow rapidly into the brake cylinder until a desired minimum pressure has been attained, whereas from that time the compressed air which is still required can flow automatically into the brake cylinder only through a narrow throttling aperture, so that the further rise of the braking pressure proceeds but slowly.

2. A compressed-air railway brake as claimed in claim 1, characterized thereby that the control piston and the control slide

valve of the brake control valve control the flowing over of the compressed air from the auxiliary air reservoir (and the train pipe) into the brake cylinder in such a manner that on initiating the braking air from the auxiliary reservoir (and from said pipe) flows rapidly into the brake cylinder until the desired minimum pressure has been attained at which the strong flowing over from the auxiliary reservoir (and the flowing over from the train pipe) is interrupted, whereas the compressed air still required (at least the greatest part thereof) flows into the brake cylinder from that time solely from the auxiliary air reservoir through a narrow throttling aperture of the brake control valve.

3. Compressed air railway brake comprising a train pipe, a brake cylinder and an auxiliary reservoir, a casing connected with said train pipe, cylinder and reservoir, and a control piston adapted to reciprocate in said casing under the influence of the air pressure in said train pipe and adapted to control the connection of said casing with said train pipe, cylinder and reservoir, the connection of said brake cylinder and said casing with said reservoir comprising two passages of different areas, said control piston being adapted in a predetermined position to close the wider one of the two passages while leaving open the narrower passage.

4. Compressed air railway brake comprising a train pipe, a brake cylinder and an auxiliary reservoir, a casing connected with said train pipe, cylinder and reservoir, and a control piston adapted to reciprocate in said casing under the influence of the air pressure in said train pipe and adapted to control the connection of said casing with said train pipe, cylinder and reservoir, the connection of said brake cylinder and said casing with said reservoir comprising two passages of different areas and different lengths, said control piston being adapted to close in a predetermined position the wider and longer one of the two passages while leaving open the narrower and shorter passage.

5. Compressed air railway brake comprising a train pipe, a brake cylinder and an auxiliary reservoir, a casing connected with said train pipe, cylinder and reservoir, and a control piston adapted to reciprocate in said casing under the influence of the air pressure in said train pipe and adapted to control the connection of said casing with said train pipe, cylinder and reservoir, the connection of said brake cylinder and said casing with said reservoir comprising two passages of different areas, said control piston being adapted in a predetermined position to close the wider one of the two passages while leaving open the narrower

passage, and a shut-off valve adapted to control the passages.

6. Compressed air railway brake comprising a train pipe, a brake cylinder and an auxiliary reservoir, a casing connected with said train pipe, cylinder and reservoir, and a control piston adapted to reciprocate in said casing under the influence of the air pressure in said train pipe and adapted to control the connection of said casing with said train pipe, cylinder and reservoir, the connection of said brake cylinder and said casing with said reservoir comprising two passages of different areas, said control piston being adapted in a predetermined position to close the wider one of the two passages while leaving open the narrower passage, and a shut-off valve comprising ports of different areas, and means for alternately connecting the ports with the passages.

7. Compressed air railway brake comprising a train pipe, a brake cylinder and an auxiliary reservoir, a casing connected with said train pipe, cylinder and reservoir, and a control piston adapted to reciprocate in said casing under the influence of the air pressure in said train pipe and adapted to control the connection of said casing with said train pipe, cylinder and reservoir, said casing comprising a passage adapted to be controlled by said piston for conducting into the brake cylinder the compressed air in the space of said casing which is connected with the train pipe and in which said control piston reciprocates, said control piston being adapted to close the passage when the rate of pressure increase in the brake cylinder is being reduced.

8. Compressed air railway brake comprising a train pipe, a brake cylinder and an auxiliary reservoir, a casing connected with said train pipe, cylinder and reservoir, and a control piston adapted to reciprocate in said casing under the influence of the air pressure in said train pipe and adapted to control the connection of said casing with said train pipe, cylinder and reservoir, said casing comprising a passage adapted to be controlled by said piston for conducting into the brake cylinder the compressed air in the space of said casing which is connected with the train pipe and in which said control piston reciprocates, said control piston being adapted to close the passage and a slide valve adapted to reciprocate in said control piston and to interrupt the connection between said casing and said auxiliary reservoir when said piston closes the passage.

9. Compressed air railway brake comprising a train pipe, a brake cylinder and an auxiliary reservoir, a casing connected with said train pipe, cylinder and reservoir, and a control piston adapted to reciprocate in said casing under the influence of the air

6
pressure in said train pipe and adapted to control the connection of said casing with said train pipe, cylinder and reservoir, said casing comprising two ports of different areas which are adapted to connect said casing with said brake cylinder, said control piston being adapted to close in a predetermined position the wider one of the two passages while leaving open the narrower 10 passage until said piston has reached its final position.

10. Compressed air railway brake comprising a train pipe, a brake cylinder and an auxiliary reservoir, a casing connected 15 with said train pipe, cylinder and reservoir, and a control piston adapted to reciprocate in said casing under the influence of the air

pressure in said train pipe and adapted to control the connection of said casing with said train pipe, cylinder and reservoir, a 20 slide valve adapted to reciprocate in said piston, said casing comprising two ports of different areas which are connected with said auxiliary reservoir and the inside of said casing, said slide valve being adapted to 25 open the wider one of the two ports on a reduction of pressure in said train pipe and to close it under the action of the pressure building up in said brake cylinder.

In testimony whereof I affix my signature.
IVAR DROLSHAMMER.
